UNITED STATES PATENT OFFICE.

FREDERICK BOOTH, OF MICHIGAN CITY, INDIANA.

TOOL-HANDLE GEARING.

1,183,426.

Specification of Letters Patent.

Patented May 16, 1916.

Application filed October 16, 1915. Serial No. 56,199.

To all whom it may concern:

Be it known that I, FREDERICK BOOTH, a citizen of the United States, residing in Michigan City, in the county of Laporte and State of Indiana, have invented certain new and useful Improvements in Tool-Handle Gearing, of which the following is a specification.

This invention relates to tools of the class in which a handle is provided with means for detachably connecting it with various tools or tools of different sizes, such as screw-drivers, drills, etc., and which are so constructed and equipped that by merely pushing on the handle the tool may be rotated. In such tools it is customary to so construct the mechanism that the tool ceases to revolve when pressure is released and the handle is returned to its normal position, and to provide means whereby the tool may be rigidly connected with the handle, so that it may be operated by merely turning or twisting the handle in the ordinary way.

The object of my invention is to so improve tools of this class that they are made stronger, more quick, reliable and easy in operation, less apt to get out of order, and more quickly and easily adjusted.

My invention involves certain improvements in the construction of the mechanism for rotating the tool whereby such mechanism is simplified and made to operate with reduced friction.

My improvements are illustrated in the accompanying drawings, in which—

Figure 1 shows a longitudinal central section of a combination tool handle and tool embodying my improvements. Fig. 1^a shows a longitudinal section of the handle with the spindle and parts connected therewith in elevation, the spindle being in its inner position or the position which it occupies before pressure is applied to the handle. Figs. 2, 3 and 4 are on an enlarged scale, Fig. 2 showing a transverse section on the line 2—2 of Fig. 1. Fig. 3 shows a longitudinal section on the line 3—3 of Fig. 2. Fig. 4 shows a cross section on the line 4—4 of Fig. 3.

The handle preferably comprises a hollow wooden outer part A and a metal tubular inner part A' which is rigidly connected with the wooden part and these two parts move together when the tool is operated. The inner end of the tubular part

A' is closed by a head a' to which it is rigidly secured. A rack B having oblique teeth and mounted within the hollow handle extends from the cap a' to the closed end of the handle and is rigidly secured to the tubular part A', as shown. The spindle C extends longitudinally within the handle parallel with the rack B and is adapted to move endwise relatively thereto. This spindle is connected with the tool chuck in a manner hereinafter described, and it is supported and guided by the head a' and by the sliding spindle bearing D within which the spindle rotates, but with which it moves endwise. This spindle bearing is shown in detail in Figs. 2, 3 and 4, and comprises a body portion d of general circular or cylindrical shape of approximately the inner diameter of the tube A', and it carries ball bearing d' for reducing friction to a minimum as the bearing moves back and forth in the handle. The bearing is connected to move endwise with the spindle by means of a collar d² attached to the spindle close to the bearing and by the spiral pinion E which is fixed to the outer end of the spindle.

Ball bearings e, e' are interposed between the collar, the pinion and the bearing to take end-thrust and reduce friction, and in order to lubricate the pinion, I provide a pad F, supported by a plate f and partially surrounding the pinion. The pad also serves to lubricate the inner wall of the tube A'. By this construction not only is the pinion and rack supplied with a lubricant to reduce friction, but the movement of the spindle-bearing is made easy despite the fact that considerable sidewise pressure is exerted by the bearing on its tubular guide. The pad also serves to remove from the tubular casing any dust or grit that may enter it. In other words, the pad keeps the interior of the casing perfectly smooth and clean, and therefore enables the spindle-bearing to reciprocate with a minimum amount of friction.

It will be observed that the bearing D is cut away or recessed to receive the rack B and as the bearing moves back and forth in the handle the rack is straddled by the bearing. A coiled spring Y surrounds the spindle C and is connected at one end y to the head a' and its opposite end is connected at y' to the collar d². This spring

is an extension spring, *i. e.*, it normally holds the bearing D in the position shown in Fig. 1^b, and when the bearing moves to the outer end of the handle the spring is 5 extended and put under tension and therefore tends to move the spindle away from the handle or to the position shown in Fig. 1^a.

By the construction described the pinion 10 E is made to float, as it were, in the hollow handle which serves as a guide for the spindle. Said pinion does not engage the walls of the handle nor does it necessarily rest of the rack. It is held in this way by the 15 spindle bearing D which it will be observed has the ball bearing d' in its periphery which engages the smooth inner walls of the handle. In this way friction is reduced to a minimum. It will be further observed that 20 in the operation of the tool the side thrust imparted to the pinion is received by the ball bearings e, e' which also receive end thrust. Said side thrust of the spindle is first transmitted to the balls e, e' and through them 25 to the spindle bearing and the side thrust of the spindle bearing is transmitted to the balls d' which have a rolling and easy contact with the inner wall of the handle. Friction is further reduced by the pad F 30 which serves not only to brush away dust or the like from the inner wall of the handle, but it also applies lubricating material to said wall and to the pinion and through the latter to the rack. By the construction 35 employed a very simple and inexpensive form of anti-friction device may be used in the tool.

The spindle C extends through the head a' and carries a chuck G which may be of 40 any suitable construction. Some of the details of the chuck are shown in Fig. 1, but as such details are not herein claimed they are not specifically described.

When the parts are in the position shown 45 in Fig. 1^a the tool is ready for use as an automatic tool driver. When the handle is pressed inward the pinion E, which engages the rack B, is made to rotate and move endwise toward the outer end of the handle 50 and while so doing the spring Y is extended. This movement of the spindle causes the chuck and the tool X carried thereby to rotate. As soon as pressure is removed from the handle the spring Y draws the 55 pinion E toward the head a' and to the position shown in Fig. 1^a ready for another operation and while the tool, if a screwdriver, is still in engagement with the screw. These operations can be repeated indefinitely 60 until the work is finished.

Experience has demonstrated that a tool constructed in accordance with my invention may be quickly adjusted, operates with a minimum amount of friction, is not apt 65 to bind or get out of order, and as the mech-

anism is simple it may be constructed at relatively small expense.

I claim as my invention:

1. A tool, comprising a hollow spindle guide, a rack bar having oblique teeth and disposed longitudinally in the guide on one side only of its longitudinal axis, a spindle within the guide parallel with the rack bar, a spindle bearing moving longitudinally of the rack bar with the spindle and bearing 70 against the inner wall of the guide, and a pinion fixed to the spindle and engaging the rack bar.

2. A tool, comprising a hollow spindle guide, a rack bar disposed longitudinally in the guide on one side only of its longitudinal axis, a spindle within the guide parallel with the rack bar, a spindle bearing moving longitudinally of the rack bar with the spindle, bearing against the inner wall of the guide and in which the spindle rotates, 80 and a pinion fixed to the spindle and engaging the rack bar.

3. A tool, comprising a hollow spindle guide, a rack disposed longitudinally in the 90 guide on one side only of its longitudinal axis, a spindle within the guide parallel with the rack, a spindle bearing moving longitudinally of the rack with the spindle and provided with an anti-friction bearing 95 on its periphery engaging the inner wall of the guide, and a pinion fixed to the spindle and engaging the rack.

4. A tool, comprising a hollow spindle guide, a rack disposed longitudinally in the 100 guide on one side only of its longitudinal axis, a spindle within the guide parallel with the rack, a spindle bearing through which the spindle extends, an anti-friction bearing interposed between the spindle and the spindle bearing for transmitting the side thrust of the spindle to the spindle bearing, and a pinion fixed to the spindle 105 and engaging the rack.

5. A tool, comprising a spindle guide, a 110 rack disposed longitudinally in the guide on one side only of its longitudinal axis, a spindle within the guide parallel with the rack, a spindle bearing moving longitudinally of the rack with the spindle and through which the spindle extends, an anti-friction bearing interposed between the spindle and the spindle bearing, an anti-friction bearing carried in the periphery of the spindle bearing and adapted to engage 115 the inner wall of the guide, and a pinion fixed to the spindle and engaging the rack.

6. A tool, comprising a hollow spindle guide, a rack having oblique teeth and disposed longitudinally within the guide on 125 one side only of its longitudinal axis, a spindle within the guide parallel with the rack, a pinion fixed to the spindle and engaging the rack, and a spindle bearing supporting the spindle within the guide and 130

serving to float the pinion in the guide while engaging the rack and to hold it away from the wall of the guide.

7. A tool, comprising a hollow spindle 5 guide, a rack having oblique teeth and disposed longitudinally in the guide on one side only of its longitudinal axis, a spindle within the guide parallel with the rack, a spindle bearing moving longitudinally of the rack within the guide and bearing against the inner wall thereof, a pinion fixed to the spindle and engaging the rack, and a lubricating pad carried by the spindle and engaging the inner wall of the 10 guide and the pinion.
10. The rack with the spindle and bearing against the inner wall of the guide, a pinion fixed to the spindle and engaging the rack and an extension spring attached to the guide and to the spindle bearing and serving to draw the spindle into the guide.
8. A tool, comprising a hollow spindle 15 guide, a rack disposed longitudinally in the guide on one side only of its longitudinal axis, a spindle within the guide parallel with the rack, a spindle bearing moving longitudinally of the rack with the spindle and which is recessed to receive the rack and bears on the inner wall of the guide, and a pinion fixed to the spindle and engaging the 20 rack.
9. A tool, comprising a hollow spindle 25 guide, a rack disposed longitudinally in the

guide on one side only of its longitudinal axis, a spindle within the guide parallel with the rack, a spindle bearing moving longitudinally of the rack within the guide and bearing against the inner wall thereof, a pinion fixed to the spindle and engaging the rack, and a lubricating pad carried by the spindle and engaging the inner wall of the 30 guide and the pinion.

10. In a tool, the combination of a hollow spindle guide, a spindle mounted to reciprocate therein, a spindle bearing which supports the spindle and moves longitudinally 40 therewith in the guide, a rack bar within the guide, a pinion fixed to the spindle and engaging the rack bar, an anti-friction bearing interposed between the spindle bearing and the inner wall of the guide, and a lubricating pad carried by said spindle bearing and engaging the inner wall of the guide.

In testimony whereof, I have hereunto subscribed my name.

FREDERICK BOOTH.
